AUGUST F. IHDE, OF BUFFALO, NEW YORK, ASSIGNOR TO FEEDERS MANUFACTURING COMPANY, INC., OF BUFFALO, NEW YORK

MOUNTING FOR RADIATOR SHUTTERS

Application filed July 31, 1930. Serial No. 472,098.

This invention relates to a mounting for radiator shutters and more particularly to means for mounting a shutter adjacent to the radiator of an automotive vehicle for controlling the quantity of air passing therethrough.

In the present stage in the development of motor cars employing water cooled power plants, it is customary to provide an air cooled radiator, covered by a thin, sheet metal shell, at the forward end of the vehicle, and to mount a shutter unit directly in front of the radiator to control the air passing therethrough, and thus maintain the cooling water of the engine at a substantially constant temperature under diverse weather conditions. Heretofore such shutter units have been secured to inturned flanges formed in the radiator shell, necessitating rigidifying or strengthening of that part or they have been secured directly to parts of the radiator core not especially adapted to support them by means visible from the exterior of the vehicle and detracting somewhat from the appearance of the machine.

In mounting the radiator cores, it is usual to provide resilient means so that various shocks received by the vehicle frame will not be transmitted directly to the core, the inertia of the latter being sufficient to prevent its movement in accord with small movements of the vehicle frame.

The radiator shell, however, being of lighter construction is apt to vibrate or become distorted during uneven movements of the motor car, causing rattling and undue wear of the parts of a shutter unit secured to it. The present invention contemplates the provision of means associated directly with the radiator core for mounting the shutter unit, in such a way that frame vibrations will be damped before reaching the unit, and that the mounting means will be completely obscured from vision by an independently supported radiator shell. The mounting may be effected in a simple and

economical manner without substantially changing the design of the core proper or the radiator shell.

These and other objects and advantages will become apparent from a perusal of the following description of a typical construction embodying the principles of the invention, reference being made to the accompanying drawing, wherein:

Fig. 1 is a front elevation of an automobile radiator having a shutter unit mounted thereon in accordance with the present invention.

Fig. 2 is a disassembled perspective view of a portion of a radiator shutter unit and a saddle for supporting the radiator core, one complete side bar or upright being shown at the left of the figure.

Fig. 3 is a horizontal section taken on line 3-3 of Fig. 1, showing the radiator core, supporting saddle, shutter and shell in assembled relation.

Fig. 4 is a front elevation of the radiator core attached to the supporting saddle.

As shown in Fig. 4, the radiator 10 comprising upper and lower water tanks 11 and 12 respectively and a central cooling part 13, is secured to a supporting saddle 14 adapted for attachment to the frame of a motor vehicle. The saddle includes a substantially U-shaped bar or strap having lower side portions 15 for resting on the vehicle frame and a lower central portion 16 for supporting the lower tank 12 of the radiator core, and upright or side bar portions 17, secured to the U-shaped portion and adapted to lie adjacent the side edge of the cooling portion 13. The side bars have front edge flanges 18 and struck-out lugs 19, for engaging respectively the front and rear edges of the cooling part 13 of the radiator and upper extensions 20 for positive securing, as by soldering, to the upper tank 11. The saddle being resilient affords a flexible mounting for the radiator core, of which it is a part, preventing to a

great extent the transmission of road shocks and engine vibrations to the core proper. The side and top edges of the radiator and the attached side bars are covered by a shell or radiator covering member 22, which has a front flange 23 defining a large central opening 24 for the passage of air through the core. The shell is connected to the core by brackets 25 mounted on the top tank 11 and rearwardly extending flanges 26, provided with elongated apertures 27, formed on the side bars 17 and securely held by bolts 28 to the shell adjacent to the rear edges thereof. A strap 29 is fixed to the lower side edges of the shell, as shown in Fig. 3, for mounting the shell upon the vehicle frame.

The radiator shutter unit 30 comprises a plurality of narrow slats 31, preferably of vertical extent, which are pivoted at their upper and lower ends to the top and bottom portions of a substantially rectangular shutter frame 32, the slats being operable for opening and closing movement by any suitable means (not shown) to control the quantity of cooling air passing through the radiator core. Laterally and outwardly extending ears 34 are provided on the side portions of the frame 32, preferably co-planar with the rear face of the shutter unit, as shown in Fig. 3, and similar ears 35 are provided on the forward edge of the side bars 17. The ears 34 and 35 are apertured as indicated at 36 for the reception of bolts or other suitable securing means 37.

It will be seen that in this manner the shutter unit 30 is secured to the radiator side bars by means entirely independent of the radiator shell, the opening 24 formed therein being larger than the frame 32, as shown in Fig. 3, so as not to contact therewith. The shutter unit, being mounted directly upon the resilient saddle, which forms a part of the radiator, will, as the core itself, be protected from severe road shocks and engine vibrations which if transmitted to the unit would tend to bring about undue wear of the movable slat parts with attendant rattling of these members during operation of the vehicle. The radiator shell, having an independent mounting is capable of limited flexing or distortional movement relative to the shutter unit and need not be rigidified or altered in any way to carry the unit. It will be further understood that the specific structure described may be modified in various details, and it is intended that the invention should be commensurate with the scope of the following claims.

What is claimed is:

1. In combination with a radiator, a saddle for resiliently mounting said radiator to a vehicle, said saddle including upright bars attached to said radiator, a radiator shell connected to said saddle and provided with a central opening, and a shutter unit extending

through said central opening and secured directly to said saddle.

2. The combination of a radiator, a radiator shell having a central opening, said shell being connected to said radiator, and a shutter unit substantially filling the opening in said shell and secured to said radiator independently of said shell.

3. The combination of a radiator, a radiator shell having a central opening, said shell being connected to said radiator, and a shutter unit substantially filling the opening in said shell and secured to said radiator by means independent of and obscured from view by said shell.

4. The combination of a radiator, a radiator shell having a central opening therein, a shutter unit adjacent to said radiator and disposed in the central opening in said shell, and means independent of said shell for connecting said unit to said radiator, said shell substantially encasing said means.

5. In combination with a radiator having upright strips secured to the lateral edges thereof, said strips having laterally extending ears formed therewith, a radiator shutter unit, comprising a plurality of shutter slats and a substantially rectangular frame for mounting said slats, disposed adjacent to said radiator, said frame having laterally extending flange portions for engagement with the ears formed on said strips, and a radiator shell adapted to be fastened about said radiator and saddle members, said shell having a central opening through which a portion of said shutter extends.

6. In combination with a radiator having laterally extending ears formed on the side edges thereof, a radiator shell adapted to be secured about said radiator and having a large central opening therein, a radiator shutter unit, including a frame with laterally extending flange portions, extending through the opening into said shell, and means for securing said ears to said flange portions, whereby said shutter unit is supported on said radiator independently of said shell.

7. In combination with a radiator, a saddle for supporting the radiator, a radiator covering member having portions thereof defining a central opening, the covering member being supported by the saddle, and a shutter unit secured to the saddle independently of the covering member, the shutter unit lying adjacent the portions of the covering member defining the central opening.

8. In combination with a radiator, a supporting saddle therefor having ears, a shutter unit having ears secured to said first mentioned ears, and a radiator covering member secured to the supporting saddle independently of the shutter unit and having a central opening in alignment with the shutter unit and radiator, the covering member concealing said ears.

9. In combination with a radiator, a radiator shell and a radiator shutter to be mounted upon a vehicle frame, a saddle having a portion adapted to be attached to the vehicle frame, another portion secured to the upper part of the radiator, flanges on the saddle for supporting the radiator shell, and means independent of said shell and the supporting flanges therefor for mounting the radiator shutter upon the saddle.
